METHOD OF MAKING COKE FROM
HYDROCARBON RESIDUES

Albert P. Sachs, New York, N. Y., assignor to
Petroleum Conversion Corporation, Elizabeth,
N. J., a corporation of Delaware

Application July 6, 1938, Serial No. 217,670

4 Claims. (Cl. 202—5)

My present invention relates to improvements in the art of coking heavy hydrocarbon oil, especially the residues from oil cracking systems. The main object of the invention is to produce coke extremely low in or substantially free from volatile matter.

In carrying out my invention in its preferred embodiment I introduce a charge of oil to be coked, which preferably has been suitably freed from lighter components, into the coking vessel to fill the same to a fraction only of the height of the coking vessel, whereupon I bring about coking of the charge preferably by introducing into the body thereof a heated non-liquid, fluid heat carrying medium, e. g., hydrocarbon or other inert gas or hot hydrocarbon vapors from a cracking or reforming operation. After the initial charge in the coking vessel has been thus coked, the supply of heating medium is stopped, or at least 15 greatly diminished, and the contents of the coking vessel subjected to the action of a relatively high vacuum to thereby remove volatile matters in the coke. After the desired effect has been had by the action of the vacuum, the vacuum pump, 20 steam vacuum jet or other means of producing the vacuum is cut off, the heat carrier admitted for a short time to warm up the residual coke, whereupon a fresh supply of oil to be coked is charged above the coke body and the coking operation continued. In this manner the charge of coke in the vessel is gradually built up while subject to vacuum action as each increment of coke is formed.

The invention will be best understood by reference to the following detailed description taken with the accompanying drawing, the single figure of which shows diagrammatically a plant embodying a preferred form of the invention.

For the sake of illustration the invention is shown in connection with a type of cracking process, known in the art as the TVP process, although residual oils from other sources may be used, and the present coking operation may be used in connection with any type of cracking process. Designating first the cracking system, cracking stock is admitted to vaporizer 1 through pipe 2 wherein it is heated and subjected to flash vaporization in the flash drum 3, being admitted thereto through pipe 4. The released vapor leaves the drum 3 through pipe 5 through which it is conducted to a superheater 6. The superheated vapor leaves the heater 6 through pipe 7 by which it is conducted to reaction chamber 8. At the same time a gaseous heat carrier, as for example the residual gas of the cracking system, is heated up

in the furnace 9 to a temperature somewhat higher than that of the vapors from superheater 6, is conducted from furnace 9 through pipe 10 and mingles with the vapors in pipe 7, the mixture of gas and vapors thereupon being admitted to the reaction chamber 8. The vapors become cracked in said reaction chamber and the mixture of the gas and cracked vapor leaves the same through pipe 11 by which it is conducted to fractionator 12. In said fractionator the cracked products are separated into an overhead fraction containing the gasoline vapors which leaves through pipe 13 and is subjected to various recovery and refining treatments usual in the art, by means not shown, and a bottoms fraction which is withdrawn through pipe 14. Various intermediate fractions are also produced including a recycle stock which it is not necessary to describe, and the fractionator is refluxed as is usual in the art, but the means therefor are not shown.

The residue to be coked leaving through pipe 14 is preferably subjected to the stripping action, at a pressure lower than the fractionator pressure of an atmospheric stripping tower or flash drum 15 (the pressure obtaining in the fractionator being, say, of the order of 50 to 100 pounds per square inch gage) wherein the overhead of lighter vapors is produced leaving through pipe 16, passing through condenser 17 communicating with which is accumulator 18. The condensed distillate collecting in 18 may be used as recycle stock or for other purposes. The stripped residue, say, by way of example, of a gravity of 7° or 8° A. P. I., leaves the stripper 15 through pipe 20 by means of which it passes to coking vessel 21. Pipe 20 may be provided with a pump not shown or the flow of stripped residue may be carried out by the difference in pressure, coking chamber 21 being operated at a lower pressure than flash tower 15. Preferably pipe 20 has a plurality of valved connections or inlets 22a, 22b, etc., to the drum 21 spaced throughout substantially the height thereof, by means of which the oil to be coked can be introduced at different levels of the drum. For example, in a drum 20 feet high the inlets 22 may be at two-foot intervals. Although one inlet at the top may be sufficient, a plurality of inlets is provided to guard against the danger of the coking up of that one inlet. Heated gas or hot products from a cracking or reforming operation from a source not shown are introduced into the drum 21 through pipe 23 and any one of spaced valve connections 24a, 24b, etc., as may be desired.

At the start of the coking operation a measured amount of oil is admitted to the drum 21,

by valve 22a or any other convenient inlet sufficient to give a coke charge of a height not exceeding the second inlet connection 22b. Hot gas or other coking medium is then admitted 5 from pipe 23 through connection 24a for a sufficient time to bring about coking of the charge, the overhead products leaving the drum 21 through pipe 25, through which they pass to a condenser 26 in communication with which is 10 an accumulator 27 for condensate, the residual gas being removed through pipe 28 to a disposition not shown. Where hot cracked vapors are employed as the coking medium the overhead products may be led off through branch pipe 25a 15 back to the fractionator 12 or may be condensed in 26, accumulated as liquid in 27 and pumped to any part of the system as desired. When the charge has been coked the admission of gas or vapor through pipe 23 to the coking vessel 21 20 is either shut off or closed down so that only a slight quantity is admitted. The vacuum pump 30 having been started is placed in communication with the drum 21 through pipe 31 having therein valve 32, accumulator 27, condenser 26, 25 pipe 25, pipe 28 being closed off by means of valve 28a. Branch line 25a is likewise valved off. The action of the vacuum is to remove substantially all of the volatile content of the charge of coke formed, after which line 31 to the pump 30 is closed off by closing valve 32, the coke charge 35 preferably warmed by admitting some of the hot gas to the drum 21, whereupon valve 22b, or any higher inlet valve, is opened and a fresh charge of residue oil admitted, and a second layer of coke is built up and again subjected to the action of vacuum in a manner already described, the process being repeated until the capacity of the drum 21 is reached, making use of the valve connections 22a, 22b, 22c, 22d, etc. 40 A plurality of gas connections 24a, 24b, 24c, 24d, etc., is also provided, should it be necessary to add the gas higher in the drum 21 as the formation of coke progresses. If, as mentioned, a slight amount of the coking medium, gas or hot vapors, 45 etc., is admitted during the vacuum operation, the stripping operation of the volatiles is facilitated. Steam may also be used to carry out the stripping operation, and if desired steam preferably superheated may be used as the heating medium in the coking operation.

50 When the capacity of drum 21 for coke has been reached, the entire charge is removed in the usual manner and, if necessary, the coking is continued in one or more other coking drums similar to 21.

Various changes in the method above given in detail will occur to those skilled in the art, without departing from the spirit of my invention or the scope of the appended claims.

I claim:

1. In a system of cracking hydrocarbon oils in which the oil is cracked in the vapor phase in a reaction chamber and the products therefrom are withdrawn and passed to a zone of fractionation, the method of handling the residue 10 from the fractionation zone which comprises the steps of passing a charge of bottoms therefrom to a coking vessel to yield a coke layer which will be a fraction only of the capacity of such vessel and building up therein a layer of coke by passing through said charge hot cracked vapors from a further cracking operation, withdrawing from the coking vessel the hot cracked products admixed with vapors produced in the coking operation and passing such admixture back to the 20 fractionating zone and admitting same thereto at a point above the withdrawal of the bottoms, subjecting the coke so formed to the action of vacuum to remove therefrom volatile matter in the coke, discontinuing the vacuum action, adding a fresh charge to the devolatilized coke so formed and continuing the stated operations of coke formation and devolatilization until a pre-determined depth of coke is built up.

2. The method of coking which comprises the 30 steps of depositing a coke yielding hydrocarbon in a vessel to a fraction of the depth thereof to yield a comparatively thin layer of coke such that upon subsequent application of vacuum the coking layer formed will be readily devolatilized, 35 coking the hydrocarbon so deposited, then applying vacuum thereto to devolatilize the same, discontinuing said vacuum when the devolatilization is substantially completed, thereafter adding a fresh charge of said hydrocarbon to the devolatilized coke so formed and continuing the operations of coke formation and devolatilization as aforesaid to build up stepwise a predetermined depth of coke in the vessel.

3. The method according to claim 2, in which 45 the coking is brought about by the action of a substantially inert heated non-hydrocarbon liquid which is passed through the hydrocarbon to be coked.

4. The method according to claim 2 in which 50 a reduced stream of heating fluid is supplied to the coking vessel during the vacuum action to promote the removal of volatile matter.

ALBERT P. SACHS.
